UNITED STATES PATENT OFFICE

164,288

COMBINED PORTABLE MOTION-PICTURE PROJECTING MACHINE AND CARRYING CASE THEREFOR

William C. De Vry, Chicago, Ill., assignor to De
Vry Corporation, Chicago, Ill., a corporation of
Illinois

Application August 18, 1950, Serial No. 11,821

Term of patent 7 years

(Cl. D61—1)

To all whom it may concern:

Be it known that I, William C. De Vry, a citizen of the United States, and a resident of Chicago, in the county of Cook, and State of Illinois, have invented a new, original, and ornamental Design for a Combined Portable Motion-Picture Projecting Machine and Carrying Case Therefor, of which the following is a specification, reference being had to the accompanying drawings forming a part thereof, and in which:

Fig. 1 is a perspective view of a combined portable motion-picture projecting machine and carrying case therefor, showing my new design;

Fig. 2 is a perspective view of the same from the opposite end;

Fig. 3 is a perspective view of the same with the cover opened.

I claim:

The ornamental design for a combined portable motion-picture projecting machine and carrying case therefor, as shown.

WILLIAM C. DE VRY.
